HOWARD C. LIEBING, OF CLEVELAND, OHIO, ASSIGNOR, BY MESNE ASSIGNMENTS, TO THE CUNO ENGINEERING CORPORATION, OF MERIDEN, CONNECTICUT, A CORPORATION OF CONNECTICUT.

COMBINED TROUBLE LIGHT AND CIGAR LIGHTER.

Application filed November 20, 1924. Serial No. 751,033.

This invention relates to a combined trouble lamp and cigar lighter. More particularly it comprises a casing adapted to be attached to the instrument board of an automobile, or some other readily accessible place, and carry at the end of an extension cord a cigar lighter or trouble lamp, according to the particular needs of the user of the device.

10 Cigar lighters carried upon automatic reels have heretofore been used on the instrument board of automobiles, but such devices are subject to certain disadvantages. In many of such constructions the cigar lighting filament commences to glow before the device has been moved any great distance from its fully retracted position and continues to glow until it is restored to its original position. If, in the interval, the 15 device is dropped, it will burn whatever it comes into contact with, and if, because of the weakness of the recoiling spring or any misadjustment of the device, the terminal is not restored to fully retracted position, 20 the current continues to charge the filament and in the course of time will short circuit the device, or through the large amount of heat developed, will melt the soldered connections and burn the insulating coating 25 off the wires.

Such cigar lighters have but a single purpose, and cars so equipped are frequently also equipped with an automatic trouble lamp on an automatic reel which may be loaded with any predetermined length of cable extension.

The principal object of the present invention is to provide an improved device wherein in a single automatic reel incorporating an improved switch may be utilized as part of a combination wherein a cigar lighting terminal is employed or a trouble lamp bulb. Another object of the invention is to provide an improved switch which will turn the current on or off, in accordance with the direction of motion, and thus prevent injury through the dropping of the cigar lighter after its momentary use and during the period when it is being restored to its origi-

nal position, as well as providing for the 50 temporary detachment of the recoiling spring of the reel when the device is used as a trouble lamp. Still further objects of the invention will appear in the course of the following description. For the accomplishment 55 of the foregoing and related ends, said invention, then, consists of the means hereinafter fully described and particularly pointed out in the claims.

The annexed drawings and the following 60 description set forth in detail certain mechanism embodying the invention, such disclosed means constituting, however, but one of various mechanical forms in which the principle of the invention may be used.

In said annexed drawings:

Fig. 1 is a side elevation of the device showing the same applied to the instrument board of an automobile with the cigar lighting terminal in fully retracted position; 70 Fig. 2 is a view similar to Fig. 1, with the cover portion of the device removed so as to illustrate the spiral switch operating groove upon one plate of the reel; Fig. 3 is a front elevation of the device with the cigar lighting element in position; Fig. 4 is a transverse central sectional view through the reel and casing showing the switch in the "off" 75 position; Fig. 5 is an elevation showing the inside of the casing with the switch 80 lever attached thereto; Fig. 6 is a greatly enlarged longitudinal sectional view of the cigar lighting unit showing the means of securing the heating element to the lava base and the metal connecting sleeve 85 secured thereto; Fig. 7 is a bottom plan view of the device shown in Fig. 6, also upon an enlarged scale; Fig. 8 is a side elevation of the trouble lamp in position within its enclosing sleeve, said sleeve being shown in section; Fig. 9 is a bottom plan view of the 90 terminal element; Fig. 10 is a longitudinal sectional view showing the terminal base with the spring contact elements for the lighting and heating unit; and Fig. 11 is a 95 bottom plan view of said terminal element shown in Fig. 10.

As is clearly shown in the drawing, the

device comprises a casing 1, formed of a box-like main body portion 2, and a cylindrical extension 3, terminating in a front plate 4, which may be of substantially triangular outline. The box-like body portion is of circular outline and comprises two parts 5, 6, adapted to be telescopically engaged with each other upon a central line. One of said parts is provided with a circular extension 7, adapted to serve as a spring housing. A reel carrying a flexible cord is adapted to be carried within said flexible casing and the free end of said cord is equipped with a terminal sleeve 9 within 15 which a cigar lighting element or a trouble lamp may be secured, according to the use to which the device is to be put.

As is particularly shown in Fig. 4, an axle 11 is mounted transversely of the casing, 20 having its ends projecting through central apertures in the sides thereof, and at one end is provided with a screw-threaded shank 12 upon which a knurled head 13 is adapted to be engaged when turned in a counter-clockwise direction. The knurled head carries on its inner face a locking pin 14 adapted to be seated within one of a plurality of apertures 15 through the side of the casing, said knurled head being held against the face of 25 said casing by means of a coiled spring 16 secured beneath a washer 17 held in place on the other end of said axle by a screw 18 tapped in the body portion thereof. A reel comprising a hub portion 21 seated upon the axle 30 and a pair of flanges 22, 23 is adapted to carry between said flanges a flexible cable 24. Said cable is provided with a pair of conductors 25, 26, one of which is secured by means of a screw 27 to the hub portion of 35 said reel, and the other of which is clipped to the flange 23 which is mounted on said hub but insulated therefrom by means of a fiber disc 28.

The disc 23, which, as stated, is insulated 40 from the supporting hub, is provided with a grooved outer face, as is more clearly shown in Fig. 2 of the drawing. This grooved outer face comprises an outer shallow groove or 45 guide path 31 of circular or non-progressive outline and an inner shallow groove or path 32 of circular or non-progressive outline. Said shallow circular grooves are connected with each other by means of a spiral groove or progressive cam path 33 extending from 50 said outer groove to said inner groove in a clockwise direction and being of slightly greater depth than either of said circular grooves. Said spiral groove is approximately one full revolution of said reel in length 55 and is adapted to operate the automatic switch of the apparatus when said reel is turned one full revolution in either direction, as will be hereinafter explained.

When the device is attached to a metal 60 instrument board one of the conductor cables

connecting with the hub of the reel is in grounded connection with the battery. The other of said cables is secured to an insulated disc and connection with the positive lead from the battery or from the ammeter is obtained through a switch provided on the inner face of the casing. Said switch comprises a spring metal strip 35 having a stud 36 at its free end adapted to ride within the grooves on the flange 23. The opposite end of said switch element is pivotally mounted upon a pivot pin 37 insulated from the casing by means of an insulating block 38. An insulated contact pin 39 is provided, spaced a short distance from the insulated pin 37, securing the switch member to the casing and is provided on its inner end with a beveled end 41, over which the switch member has wiping contact. Said insulated contact pin 39 is connected with the positive pole of the battery by suitable attachment 42. Thus, each time the spring contact is wiped across the beveled head, current is established in the cigar lighting filament or through the trouble lamp, whichever attachment happens to be in place in the terminal socket of the device.

The flange of the reel opposite to the flange provided with the grooved surface is provided with an extension casing 51 secured centrally thereto and housing a coil type spring 52 secured at its inner end to a hub 53 by means of a pin 54 and having its outer end clipped beneath a lug 55 struck inwardly from the side of the casing. The spring is adapted to rotate the reel in a counter-clockwise direction and is of sufficient length to permit a liberal quantity of cord to be carried by the reel so that the cigar lighting terminal may be used by a person in the rear seat of a large car.

The cylindrical extension through which the free end of the flexible cable extends is secured to the casing by means of a pair of short bolts 61, passing through the flange base 62 thereof. At the point where said cylindrical extension is attached to the body portion of the casing the flanges at its circumference are cut away to provide an aperture 63 through which the flexible cable may 65 be freely drawn. The cylindrical extension terminates in a front plate 4 of substantially triangular outline and is provided at its lower central portion with an inwardly projecting flange 64 which telescopically engages the forward end of said cylindrical extension. Adjacent the sides of the upper portion of said front plate apertures 65 are provided, through which fastening bolts 66 may be inserted to secure the device to the 70 instrument board of an automobile, or to some similar point of attachment.

As shown in Fig. 8, the terminal sleeve 75 9 comprises a sheet metal shell, preferably of aluminum, having a cylindrical body por-

tion and a flanged and beaded outer end 71 forming the gripping portion of the device. The sleeve is provided with slots 72 adjacent its outer portion, having right angled locking sections to receive studs 73 upon the base of the trouble light bulb 71, or similar studs 75 upon the sleeve 76 mounted about the lower portion of the composition base 77.

The trouble lamp comprises the usual miniature bulb of suitable candle power and voltage. The composition base, as is clearly disclosed in Fig. 6, comprises a lava base of cylindrical form provided with a flanged head 78, having a shallow recess 79 formed in its outer face. A longitudinal passageway 81, formed centrally through the base, communicates with said recessed portion, and a similar passageway 82 is provided through said base at one side thereof adjacent the margin of the shallow recess. Adjacent each of the said passageways a recess 83 of shallow depth is formed, said last-named recesses providing seats for the ends of the heating wire, as will be hereinafter described. Said heating wire is formed of suitable resistance material 84, coiled in spiral form and seated within the shallow recess on the face of the lava base. The ends of the wire are passed respectively through the central and lateral passageways through the base and are then turned sharply at right angles and seated in the shallow recesses 83 adjacent the respective longitudinal passageways. Through the means just described the heating wire is secured to the lava base without the use of solder and by the simple expedient of seating the ends of the wire within suitable sockets. The portions of the wire 85, which lie across the bottom face of the lava base, are so spaced as to form proper contact elements to co-operate with the spring fingers held within the terminal sleeve at the end of the flexible cable. As has been before stated, the lugs 75 are carried upon the sleeve 76 mounted upon the lower portion of the composition base, and this sleeve may be attached thereto by having its upper edge 86 spun into an annular recess 87 formed about the lava base adjacent the extension head thereof. In order to hold this sleeve against radial movement, the studs 75 are provided with heads 88, which fit within holes 89, formed longitudinally of the lava base at diametrically opposite points.

In order to permit the ready handling of the terminal sleeve the flange thereof is spaced from the trouble lamp bulb or the cigar lighting element a sufficient distance to permit the circulation of air between said flange and the unit employed in the terminal sleeve. Where said terminal sleeve is made of aluminum, this spacing of the flange from the interchangeable unit provides a means for handling said sleeve without danger of burning the finger-tips, inasmuch as the

radiation of the heat is brought about so quickly and so thoroughly by this construction.

As is shown in Figs. 8 and 9, the terminal sleeve has its bottom portion 91 provided with an opening 92 of cross-like form, the respective ends of said opening being adapted to receive the fastening screws 93 and conducting cables 25, 26, of the sectional contact plug 94, which is housed within the base 70 of said terminal sleeve. Said contact plug, as is shown in Fig. 10, is formed in two sections, the main body portion 95 of which is provided with a pair of longitudinal openings 96, within which are housed on one side 75 of said body a pair of fixed contact members 97, having conical heads, and on the other side of said body a pair of spring-pressed contact fingers 98 slidably mounted in metal ferrules 99. The inner ends of said contact fingers are provided with heads 101 against which coil springs 102 bear, the opposite ends of said springs resting against the under faces of the fixed contact heads 90 heretofore referred to.

The cap section of the contact plug 103, like the body portion thereof, is formed of insulating material and is provided on one face with conical sockets 104 adapted to register with the conical heads of the body portion of said plug. Said conical sockets communicate with cylindrical passageways 105, which receive the flexible conducting cables 25, 26. A pair of screws 93 serve to hold the cap section of the contact plug 100 against the body portion thereof. These screws also serve to press the individual strands of the multi-strand conducting cable in firm contact with the surface of the fixed contact member. This connection is illustrated in Fig. 10, wherein the individual strands of the multi-strand conductors 25, 26, are spread mushroom fashion about the conical surface of the contact members 97 and are held securely clamped thereagainst 105 by means of the conical socket portion of the cap member. The screws 93 are firmly seated in said body member so as to maintain said clamping action against said wires under all conditions of strains placed upon them through the handling of the terminal sleeve with either the trouble lamp or cigar lighting unit in place.

The terminal sleeve is slipped over the conducting cables before they are secured to the contact plug and said contact plug is held firmly in the lowermost position within said terminal sleeve when either the cigar lighter or trouble lamp unit is in place.

The operation of the device has been indicated in the description of this construction, but it should be pointed out that the various features of the construction have been developed with a view to simplicity of manufacture and ease of assembly, as well as to 125 130

secure an improved result from the stand-point of operation. The wiping contact of the switch, produced by the swinging back and forth of the spring lever, insures perfect contact under all operative conditions. The device, when used as a cigar lighter, is free of the difficulty experienced with many cigar lighters wherein the flexible cable will separate from the contact plug owing to the tension being placed largely upon an individual strand of a multi-strand cable. By having the clamping elements engage each individual strand of such cable, the strain placed upon the same by the recoiling spring of the apparatus can be easily sustained and there is practically no trouble arising from the breaking of the cable at the usual points of connection.

Another feature of importance is the simple construction of the heating element wherein a resistance wire is coiled in suitable shape upon a lava base and is held in position by having its free ends seated within sockets on the under face of the same. Through having the adjacent ends of the resistance wires exposed on the under face of the lava base in the proper position of contact with the spring pressed fingers of the contact plug a substantial contact is provided for with a minimum of expense.

When it is desired to use the device as a trouble lamp instead of as a cigar lighter the recoiling spring may be released from its active position by pressing inwardly upon the end of the axle shaft 11 which projects from the spring housing. When the axle is so forced to one side the locking pin 14 is disengaged from one of the apertures in the adjacent casing and the knurled screw may rotate freely with the axle until the spring tension has been relieved. The full length of the conducting cable carried upon the reel may then be used by the person handling the trouble lamp without danger of having the reel suddenly become active, as not infrequently happens with trouble lamps carried upon reels having an automatic ratchet control. When it is desired to rewind the flexible cable and restore the terminal sleeve to its normal position, the knurled head is turned the necessary number of times to place the desired degree of tension upon the recoiling spring.

It will be noted that the switch is operated either to establish or break the circuit with approximately one full rotation of the reel, and that the current is turned on immediately after the terminal sleeve has been removed from its housing and is turned off immediately after the recoiling action of the spring begins. Thus, the resistance wire will be heated to the required degree to light a cigar by the time it has gone from its seat to the point at which it is to be used for cigar lighting purposes and the current will

be turned off and the element cooled to substantially its normal condition before the terminal sleeve is restored to its housing. If, for any reason, the complete return of the terminal sleeve is not desired, as where a party in the rear seat of an automobile first uses the device to light a cigar and later a party in the front seat of an automobile desires to use the same, it is unnecessary to return the terminal sleeve to its usual position, as the resistance wire may be restored to heated condition by merely drawing the flexible cable in an outward direction for a short distance at any point within its line of travel.

This device, while automatic, is free of the defect found in many automatic devices in that the spring tension may be regulated at all times to an amount sufficient to fully restore the terminal sleeve to its fully retracted position, but in addition to this feature of the construction, if at any time the spring is not tensioned to an amount to fully retract the terminal sleeve, the resistance wire will not be maintained in an active condition while projecting to a greater or less extent from its fully seated position. Thus, the complete safety of the device is provided for through having a spring, the tension of which may be controlled at all times, as well as through the construction providing for the automatic cut-off of the current as soon as the recoiling operation takes place.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In an article of the character described, the combination of a reel, a flexible cable carried by said reel, a spring for recoiling said reel, a switch separate from said reel, means associated with said switch for moving the same into and out of contact in accordance with the direction of motion of such reel, and means for rendering said recoiling spring inactive.

2. In an article of the character described, the combination of a reel, a flexible cable carried by said reel, a spring for recoiling said reel, a switch separate from said reel, means associated with said switch for moving the same into and out of contact in accordance with the direction of motion of such reel, and means for releasing the tension upon one end of said recoiling spring so that the tension thereof may be relieved.

3. In an article of the character described, the combination of a casing, an axle positioned centrally of said casing, a reel rotatably mounted upon said axle, a recoiling

spring secured at one end to said reel and at its other end to said axle, a switch separate from said reel, means for releasing said axle from said casing to relieve the tension on said spring, and means for turning said switch to active position as said cable is drawn from said reel.

4. In an article of the character described, the combination of a reel, a flexible electrical conductor mounted on said reel, a switch adjacent said reel, a pair of concentric grooves provided on one side of said reel, a member on the free end of said switch adapted to be seated within said grooves, and a spiral groove connecting said grooves to shift said member from one of said concentric grooves to the other in accordance with the direction of rotation of said reel.

5. In an article of the character described, the combination of a reel, a flexible electrical conductor mounted on said reel, a switch adjacent said reel, a pair of concentric grooves of shallow depth provided on one side of said reel, a member on the free end of said switch adapted to be seated within said grooves, and a groove of greater depth connecting said grooves to shift said member from one of said concentric grooves to the other in accordance with the direction of rotation of said reel.

6. In an article of the character described, the combination of a reel, a flexible electrical conductor mounted on said reel, a switch element movably mounted adjacent said reel, a fixed contact member mounted adjacent said movable switch element, a pair of concentric grooves provided on one side of said reel, a member on the free end of said switch element adapted to be seated within said grooves, and a spiral groove connecting said grooves to shift said member from one of said concentric grooves to the other in accordance with the direction of rotation of said reel and to swing said movable member into and out of contact with said fixed contact member.

7. In an article of the character described, a casing, an axle secured centrally of said casing, a reel pivotally mounted upon said axle, a switch adjacent said reel, a spring housing carried upon said reel and within an extension of said casing, a spring secured at one end of said housing and at its other end to the hub keyed upon said axle, means for holding said axle against rotation with respect to said casing whereby said spring may be placed under a predetermined degree of tension, means associated with said reel for moving the switch into and out of contact position in accordance with the direction of motion of said reel, and means for releasing said axle from engagement with said casing to relieve the tension upon said spring.

8. In an article of the character described,

a casing, a reel mounted within said casing and adapted to carry a flexible electrical cable, a switch adjacent said reel to control a circuit through said cable, means for retracting said cable, means for rendering said reTRACTING means inactive, and means for shifting said switch out of contact position when said reel moves in a direction to retract said cable.

9. In an article of the character described, the combination of a reel to carry a flexible electrical conductor, a switch comprising a switch member for opening and closing a circuit through said conductor, a cam turning with said reel and having two complete non-progressive guide paths and a progressive guide path joining the two non-progressive paths, and a follower on said switch member engaged in said paths and adapted to pass from one of said complete guide paths into said progressive guide path when the direction of rotation of the reel is reversed.

10. In an article of the class described the combination of a reel to carry a flexible electrical conductor, and reel-controlled means for opening and closing a circuit through said conductor, comprising two elements relatively rotatable by said reel, one of said elements comprising a cam having two complete non-progressive paths and a progressive path joining the two non-progressive paths, a switch member on the other of said elements, and a follower on said switch member engaged in said paths and adapted to pass from one of said complete paths into said progressive path when the rotation of the reel is reversed.

11. In a device of the character described, a cam device having two complete non-progressive paths and a progressive connecting path and a switch comprising a contact arm controllable by said paths for holding in circuit-closing position by one of said non-progressive paths, for holding the switch open when controlled by the other of said non-progressive paths, and for shifting said contact arm from one position to the other by means of said progressive connecting path.

12. In a device of the character described, two relatively rotatable elements, one of said elements having two circumferentially complete non-progressive guide paths and a progressive guide path connecting said non-progressive guide paths, and a circuit closing member mounted on the other of said elements and having a follower engaged in said paths for actuation by said connecting path and for retention in circuit-closing position by one of said complete paths and in open position by the other of said complete paths.

13. In a device of the character described, a cam device having two circumferentially

complete non-progressive cam paths and a connecting progressive path, and an electric switch comprising a shiftable contact member connected with a member seated in said paths and adapted to be automatically controlled by said paths.

14. In a switch, a cam having two continuous grooves, one surrounded by the

other, and a spiral connecting groove, a contact arm controlled by said grooves, and means to direct said contact arm into control by said connecting groove under certain circumstances.

Signed by me, this 12th day of November, 1924.

HOWARD C. LIEBING.
